UNITED STATES PATENT OFFICE.

HANS THEODORE HANSEN, OF MILWAUKEE, WISCONSIN.

WHEEL.

No. 851,334.

Specification of Letters Patent.

Patented April 23, 1907.

Application filed August 2, 1905. Serial No. 272,302.

To all whom it may concern:

Be it known that I, HANS THEODORE HANSEN, a citizen of the United States of America, residing at Milwaukee, in the county of Milwaukee and State of Wisconsin, have invented certain new and useful Improvements in Wheels, of which the following is a specification.

My invention relates to certain improvements in wheels of the class employing a rim composed principally of a series of radial blocks, preferably of wood or similar material, and also preferably with the grain arranged in radial lines. I have found that an all-wood rim is liable to injury upon the heavier and more powerful motor-driven vehicles, in case one of the wheels drops into a depression bounded by sharp stone or metal edges, such as are common in the streets of a large city. When this happens, the depression may be of such depth as to prevent the advance of the wheel and the latter merely rotates without moving forward and grinds off the wood against the sharp edges of the depression.

It is the purpose of my invention to reinforce the wood rim in such a way as to fortify it against the grinding action above described, and, at the same time, avoid losing the traction and other good points of the wood rim.

To such end, my invention consists in certain novel characteristics which will appear in the preferred construction, hereinafter described; and the essential features of which will be pointed out in the claims at the end hereof.

In the drawings, Figure 1 is a side elevation of the complete wheel with part of the metallic retaining portions broken away to more clearly disclose the wooden segments, and the metal reinforcements thereof; Fig. 2 is an edge elevation of the wheel with the central and lower part cut vertically in the plane 2—2 of Fig. 1, to show the lower portion of the wheel in vertical section; Fig. 3 is a perspective of one of the steel reinforcing wedges; and Fig. 4 is a perspective of one of the wooden segments.

Referring to these drawings, A, is a central hub, provided with a marginal groove, a, in which are set, preferably endways, a series of wedge-shaped blocks, B, preferably

cut away at their outer corners, as seen at, b. In the notches formed at these corners are placed two retaining annular bands or rings, 55 C, C¹, preferably angle-shaped in cross-section, so as to fit closely the reduced end portion of the block and extend inwardly over the wider portion. These retaining bands are secured together and upon the blocks by 60 means of bolts or other suitable devices, D. The meeting surfaces of the segmental blocks are cut away at their outer ends to receive preferably wedge-shaped reinforcing blocks, E, of metal or other suitable material. 65 These blocks are forced in between the wooden blocks and if desired may be provided with roughened surfaces, or other engaging devices, to prevent them from slipping outward. So far as present experience 70 teaches, however, the friction between the wedges and the wooden blocks is ample to retain the former against outward displacement. These wedges are intended to be arranged approximately flush with the ends of 75 the wooden blocks and their end areas may be so proportioned as to wear away at the same rate as the wooden part of the rim. Or, if desired, they may be made of such size as to be gradually crowded inward, as the 80 wooden blocks wear away, taking up any looseness between the latter which may develop at the outer ends from the wear and racking of the wheel.

It is possible to vary these wedges in many 85 other particulars, without departing from the spirit of the invention, hence I do not limit the latter to the precise form of construction disclosed and described.

I claim as new and desire to secure by Letters Patent:—

1. A tire comprising wooden wedges having their small ends toward the center of the wheel and the grain of which runs radially in combination with a series of radial metal 95 wedges the outer edges of which extend transversely of the tread of the wheel, said wedges being driven between the wooden wedges to form therewith a solid structure.

2. A tire comprising wooden wedges having their small ends toward the center of the wheel and the grain of which runs radially in combination with a series of radial metal 100 wedges the outer edges of which extend

transversely of the tread of the wheel, said wedges being driven between the wooden wedges to form therewith a solid structure, said metal wedges being adapted to move 5 inward as the surface of the tire is worn down.

In witness whereof I have signed the

above application for Letters Patent at Milwaukee, in the county of Milwaukee and State of Wisconsin.

HANS THEODORE HANSEN.
